UNITED STATES PATENT OFFICE.

CHRISTIAN H. LARSON, OF AVOCA, WISCONSIN.

GATE.

SPECIFICATION forming part of Letters Patent No. 690,063, dated December 31, 1901.

Application filed September 4, 1901. Serial No. 74,341. (No model.)

To all whom it may concern:

Be it known that I, CHRISTIAN H. LARSON, a citizen of the United States, residing at Avoca, in the county of Iowa and State of Wisconsin, have invented a new and useful Gate, of which the following is a specification.

The invention relates to improvements in gates.

10 The object of the present invention is to improve the construction of swinging gates, more especially the means for operating the same, and to provide a simple and comparatively inexpensive operating mechanism designed for enabling the gate to be opened and closed by a person in a vehicle or on horseback and capable of permitting a person approaching the gate at either side to remain on the right-hand side of the road and to open 15 the gate, pass through the gateway, and close the gate without dismounting from a horse or without leaving a vehicle.

The invention consists in the construction and novel combination and arrangement of 20 parts hereinafter fully described, illustrated in the accompanying drawings, and pointed out in the claims hereto appended.

In the drawings, Figure 1 is a perspective view of a gate provided with operative mechanism constructed in accordance with this 25 invention. Fig. 2 is a plan view of the same.

Like numerals of reference designate corresponding parts in both figures of the drawings.

30 1 designates a swinging gate, hinged to a post or support 2 and adapted to open in one direction only, and provided with a pivoted latch 3, which is positively held in engagement with a main keeper 4 by a weight 5.

35 The main keeper 4 extends from one side of a latch-post 6, and the weight, which is located beyond the gate, depends from the outer end of the latch-bar, which is extended beyond the keeper, as clearly illustrated in 40 Fig. 1 of the accompanying drawings. The latch is connected with the ends of an actuating rope or cable 7, which may be constructed of wire, hemp, or any other material and which extends from opposite sides of the 45 gate to uprights 8 and 9. The uprights 8 and 9, which are provided with horizontal sup-

porting-arms 10 and 11, are located at the same side of the road, and the upright 9 is provided with a supplemental keeper 12 to receive the latch, whereby the gate is positively held in its open position. The arms 10 and 11 are provided with guides 14 and 15, preferably consisting of pulleys and receiving the actuating rope or cable and supporting the same, and the said rope or cable extends outward from the uprights 8 and 9 to uprights 16 and 17, located at opposite sides of the roadway. The upright 17 is located at the same side of the roadway as the uprights 8 and 9, and the upright 16 is located at the 55 opposite side of the roadway at a point directly opposite the upright 8. The uprights 16 and 17 are provided with supporting-arms 18 and 19, and the operating rope or cable extends across the gate from these uprights, 60 being supported at an intermediate point by an upright 20. The upright 20, which is located at the same side of the road as the upright 16, is provided at its upper end with a horizontal supporting-arm 21, and guides 22 and 23 depend from the arms 18 and 21 for supporting the gate-operating rope or cable. These guides consist of pulleys mounted in 65 suitable blocks. By this arrangement the operating rope or cable is looped at each side 70 of the gate, and operating ropes or cables 24, 25, 26, and 27 are connected with the sides of these looped portions and are arranged in pairs at each side of the gate. One member of each pair of operating ropes or cables is 75 adapted to swing the gate in one direction and the other member swings the gate in the opposite direction. The operating rope or cable on the right-hand side of the road, approaching the gate, when pulled opens 80 the gate, and the operating-rope or cable at the same side of the road is adapted to close the gate after a person has passed through the gateway. The operating rope or cable 24, which is supported by a guide 28 on the 85 arm 10, extends over the pulley of the guide and is connected with the adjacent portion of the operating rope or cable at a point between the gate and the pulley. The operating rope or cable 25 is supported by a 90 guide-pulley 29 on the arm 18 of the support upright 16, and it is connected with the 95 100

actuating rope or cable at a point between the guide-pulley and the gate. The operating ropes or cables 26 and 27, which are located at the opposite side of the gate, depend 5 from guides 30 and 31 of the arms 19 and 21 and are arranged substantially the same as the said operating-ropes 24 and 25. Each end of the actuating-rope is secured to the latch of the gate, and it extends upward therefrom to 10 a pulley 32, located at the top of the gate. The pulleys 32 are located at opposite sides of the gate at the top thereof and the actuating-rope extends outward from the pulleys, and when it is pulled upon it will lift the latch 15 and release the gate. The gate is connected between its ends to a rope or cable 34, which extends upward and rearward to a pulley 35, and the said rope or cable 34 is provided with a weight 36, adapted to counterbalance the 20 gate and prevent the same from sagging. The pulley 35 is mounted in a suitable block and depends from an arm of the post or support 2.

It will be seen that the gate-operating mechanism is exceedingly simple and inexpensive 25 in construction, that it is adapted to be readily applied to an ordinary swinging gate, and that it will enable the same to be opened and closed from the right-hand side of the road 30 when approaching the gate from either direction.

What I claim is—

1. The combination with a gate, of a gate-actuating rope or cable connected at its ends 35 with the gate and extending from the same in opposite directions and looped at each side of the gate and crossing the same, guides for supporting the actuating rope or cable, and operating ropes or cables arranged in pairs at 40 opposite sides of the gate and extending from each of the sides of each looped portion of the

actuating rope or cable, substantially as described.

2. The combination with a gate, and a latch mounted thereon, of an actuating rope or cable 45 connected at its ends to the latch and extending from the gate in opposite directions and looped at each side of the same and extending across the said gate, uprights or posts located at opposite sides of the gate and provided with guides receiving the operating rope or cable, operating ropes or cables arranged in pairs at opposite sides of the gate and extending from each side of each looped portion of the actuating rope or cable, and 50 guides supporting the operating ropes or cables, substantially as described.

3. The combination of a swinging gate provided with a latch, the uprights 8 and 9 located at opposite sides of the gate and arranged at the same side of the roadway, the uprights 16 and 17, located at opposite sides of the gate and at opposite sides of the roadway, the intermediate upright 20, pulleys supported by the said uprights, a gate-actuating 65 rope or cable extending from opposite sides of the gate and looped at each side of the same and supported by the said pulleys, the operating ropes or cables arranged at opposite sides of the gate and extending from each 70 side of each looped portion of the actuating rope or cable, and pulleys supporting the operating ropes or cables, substantially as described.

In testimony that I claim the foregoing as 75 my own I have hereto affixed my signature in the presence of two witnesses.

CHRISTIAN H. LARSON.
